NOLTE LACKENBACH SIEGEL(57) CLAIM

The ornamental design for a shoe sole, as shown and described.

DESCRIPTION

FIG. 1 is a perspective top front view of a shoe sole, showing our new design.

FIG. 2 is a perspective top rear view thereof.

FIG. 3 is a perspective bottom front view thereof.

FIG. 4 is a left view thereof.

FIG. 5 is a right view thereof.

FIG. 6 is a front view thereof.

FIG. 7 is a rear view thereof.

FIG. 8 is a top view thereof; and,

FIG. 9 is a bottom view thereof.

The dash-dash-dash lines represent unclaimed environmental matter and portions of the shoe sole that form no part of the claimed design. The claimed surfaces are lined for translucency and contour. No claim is made to portions that are not shown.
